BOTTLE OR THE LIKE

Paul A. Marchant, Kansas City, Mo., assignor to Rexall Drug and Chemical Company, Los Angeles, Calif., a corporation of Delaware

Filed Nov. 26, 1965, Ser. No. 88,239

Term of patent 14 years

(Cl. D58--6)

FIG. 1

FIG. 2

FIG. 3

The essential features of my design reside in those portions set forth in full lines.

I claim:

The ornamental design for a bottle or the like, substantially as shown and described.
